UNITED STATES PATENT OFFICE

2,060,553

EAR PROTECTOR

Selma M. Burleigh, Albany, N. Y.

Application April 17, 1935, Serial No. 16,894

1 Claim. (Cl. 132—45)

This invention relates to an ear protector, mainly designed for use when one is undergoing various hair dressing operations, the general object of the invention being to provide a sanitary 5 ear protector which can be manufactured very cheaply so that it can be thrown away after once being used and the parts of which are adjustable so that the device can be made to fit persons of different sizes.

10 Another object of the invention is to so construct and arrange the parts that the device can be removed without disturbing the hair and which will not cause discomfort to the wearer and which will protect the ears of the user from hot air from a dryer.

15 This invention also consists in certain other features of construction and in the combination and arrangement of several parts, to be herein-after fully described, illustrated in the accompanying drawing and specifically pointed out in the appended claim.

20 In describing the invention in detail, reference will be had to the accompanying drawing wherein like characters denote like or corresponding parts throughout the several views, and in which:

Fig. 1 is a perspective view of the device.

Fig. 2 is a view looking towards the exterior face of an ear guard and showing how the two bands extend into the guard.

30 Fig. 3 is a section on line 3—3 of Fig. 2 and showing how the ear guard receives an ear of the wearer.

In this drawing, the letter A indicates an eye shield which is provided with a band 1 at its upper edge, this band being formed with the rest of the shield or can be suitably connected therewith. 35 The ends of the band are extended and the side edges of the extended portions are notched as shown at 2. The ear shields or guards are shown at B and each guard is formed of a body 3 having a lining 4 with portions of the lining separated from the body to form a pocket 5. The ear guard and its lining forms a recess for comfortably receiving the ear as shown in Fig. 3. A slot 6 is 40 formed in the upper portion of the front side of each ear guard for receiving the notched end of the band 1. As will be seen by inserting the ends of the band 1 more or less into the slots 6, the ear guards can be properly adjusted with the eye shield to suit the wearer.

50 Slots 7 are formed in the lower ends of the ear

guards and open into the pockets and these slots are adapted to receive the resilient band 8 which passes under the front portion of the neck of the user adjacent the lower part of the chin and as shown in Fig. 3, the ends of this band 8 are 5 pressed outwardly as shown at 9 so that by bending the end portions of the band 8, the ends can be readily passed through the slots 7 and pushed the desired distance into the pockets 5 and then the resiliency of the band 8 will hold the parts in 10 adjusted position, the frictional engagement of the end portions of the band with parts of the ear guards holding the parts together in adjusted position.

I prefer to use the device with a cap formed of 15 net material with a resilient edge, said edge being slipped over the band 1 and the upper ends of the ear guards so that the hair of the user will not be disturbed by the blower or fan or hot air device when the same is being used.

20 All of the parts are formed of material of low cost so that the device can be thrown away after being used once and as will be seen, the parts are adjusted to fit different individuals. I prefer to form the ear guards of paper pulp or parchment 25 and by sliding the end portions of the resilient band 8 up or down in the pockets 5, the pressure of the upper and lower portions of the ear guards against the wearer can be regulated and each ear guard is so shaped that there are no points 30 and corners into which scissors or combs may catch.

It is thought from the foregoing description that the advantages and novel features of the invention 35 will be readily apparent.

It is to be understood that changes may be made in the construction and in the combination and arrangement of the several parts, provided that such changes fall within the scope of the appended claim.

40 I claim:

A device of the class described, comprising a pair of ear guards shaped to fit over the ears, each composed of an outer part and a lining part, portions of the lining part being separated from 45 the body part to form a pocket, the lower end of each guard having a slot therein opening into the pocket, a bowed resilient strip having its end portions entering the slots and frictionally engaging the pocket-forming portions of the lining. 50

SELMA M. BURLEIGH.
